UNITED STATES PATENT OFFICE

CHARLES E. DAVIS, OF DAVENPORT, FLORIDA, ASSIGNOR TO GOODMAN MANUFACTURING COMPANY, OF CHICAGO, ILLINOIS, A CORPORATION OF ILLINOIS

MINING MACHINE

Application filed February 3, 1927. Serial No. 165,639.

This invention relates to improvements in mining machines and relates more particularly to the type of self-propelled vehicle adaptable for use in coal mines to transport coal cutting machines and its accessories including a power cable, about a coal mine on the rails, and beyond the rails where it is impractical or uneconomical to lay rails. It may be understood that although my invention relates primarily to mining machines, its use is not restricted to mining machines or use in mines and that it may be used to transport other equipment under other conditions.

15 The principal object of my invention is to provide an improved type of self-propelled vehicle adaptable to transport a mining machine on rails or on the mine bottom, with a novel and improved means to steer said vehicle while operating on the mine bottom, and to include an improved automatic device for carrying and reeling or unreeling an electric power cable for said mining machine.

A prior Patent No. 1,548,664, issued to me 25 August 4, 1925, relates to an apparatus of the class herein described, adapted to be operable on mine rails or on a mine bottom. My present invention improves over the apparatus in this prior patent in that I use a new and 30 novel traction means for driving my truck on the ground providing an additional geared reduction, operative when my truck is travelling on a mine bottom, but inoperative when travelling on the rails, with a novel 35 means for steering my truck, and a means whereby an improved cable reel is provided as a unit with my truck. My traction driving means also comprises a novel means for causing my device to be operable on a mine bottom and inoperable on mine rails. The 40 additional geared reduction used while operating my device on a mine bottom enables my truck to more easily traverse a rough or soft mine bottom than could be travelled with other devices used for the same purpose, since travelling on rough ground necessarily requires more power than would be needed while operating on the rails. The incorporation 45 of a cable reel as a unit of my device

eliminates the pulling of a cable reel after the device.

My invention may be best understood by reference to the accompanying drawings wherein:

55 Figure 1 is a side elevation of the device embodied in my invention with a mining machine thereon in position to move about on the rails;

60 Figure 2 is a plan view of the device embodying my invention;

65 Figure 3 is a fragmentary sectional view taken on line 3—3 of Figure 2, showing the details of the forward flanged driving wheel and the traction wheel;

70 Figure 4 is a fragmentary end elevation of the flanged and tractor driving wheels;

75 Figure 5 is an enlarged fragmentary plan view of the rearward portion of the view shown in Figure 2; and

80 Figure 6 is an enlarged fragmentary sectional view taken on line 6—6 of Figure 5.

In the embodiment of my present invention, as illustrated in the drawings, a mining machine truck indicated at 1 is provided with a body portion 2 for carrying a load which in this case comprises a mining machine 3. In the preferred form herein, the body portion 2 is provided with a pair of forward axles 4—4, which are supported in said body portion and brackets 5—5 on each side thereof. Flanged wheels 16—16 are loosely mounted on the axles 4—4 and are driven by sprockets 17—17 on said axles. Traction wheels 18—18 are also eccentrically mounted 85 on the axles 4—4, as for instance, on the outside of the sprockets 17—17 and are driven by said sprockets by a suitable geared reduction and are furthermore adaptable to be engaged or disengaged with the ground. The 90 construction of these traction wheels with the drive, and method of engaging or disengaging said wheels with the ground is one of the novel features of my invention and will hereinafter be more fully explained.

95 The rear of the body portion 2 is supported by a supporting frame 19, having axles 20—20 with supporting wheels 21—21 thereon. This supporting frame carries the actuating and steering mechanism for said truck and pro-

vides a means for supporting an electric cable reel 22, as will hereinafter more fully appear.

Referring now to the details of construction of the forward driving wheels (Figures 3 and 4) it will be seen that the flanged wheel 16 is loosely mounted on the axle 4 and has driving connection with the sprocket 17 through teeth 23 projecting from the side of the wheel 16 and meshing with jaws 24 in the hub of the sprocket 17. The sprocket 17 also has teeth 25 on its outer side which fit in jaws 26 in the hub of a pinion 27 to cause rotation of said pinion. The flanged wheel 16 also has auxiliary jaws 28 on its inner hub. These jaws permit the sprocket and wheel to be transposed so that two different track gauges may be had without necessitating the design of new parts. This is accomplished by interchanging the position of the sprocket 17 with the wheel 16 so the teeth 23 on the sprocket 17 mesh with the jaws 28 on the inner side of the wheel hub, and the teeth 23 on the outer side of the wheel hub mesh with the jaws 26 on the pinion 27.

In Figures 3 and 4 I have shown in detail the traction wheel 18 and it may be seen from these figures that said wheel is comprised of a circular disk 29 eccentrically mounted on a suitable bearing 31 on the hub of the pinion 27 and another circular disc 30 eccentrically mounted on a suitable bearing 32 on the shaft 4. Suitable bearings 37 and 38 surround the circular discs 29 and 30, respectively. A cylinder 39, having a traction tread 40 on its outer periphery and a bearing surface 41 on each end of its inner periphery with an internal spur gear 42 between said bearing surfaces, fits and rotates on the bearings 37 and 38 on the discs 29 and 30. The spur gear 42 meshes with the pinion 27. A sector 44 is integral with the disc 30 and projects outwardly therefrom. Notches 45 and 46 are provided in said sector and are adapted to be engaged by a pivotally mounted locking arm 47 which when engaged in either the notches 45 or 46 holds the disc 30 from rotation. A spacer 48 serves to space the discs 29 and 30 at the proper distance and to hold the disc 29 stationary when the disc 30 is held stationary. Studs 49 pass through said discs and spacer and hold said discs together by means of suitable nuts threaded thereon. Therefore, (with the discs 29 and 30 held stationary) rotation of the pinion 27 causes rotation of the internal gear 42 which rotates the traction tread 40 about the bearing members on the discs 29 and 30. When the locking arm 47 is in the notch 46, the traction wheel 18 will be out of contact with the ground while the flanged wheels will be in contact with the mine rails. To bring the wheels 18 into contact with the ground it is only necessary to release the locking levers 47 and start the truck in a forward direction with said locking levers released until said

locking levers can be placed in the notches 45. Additional holes 50 are provided in the sector 44 for the insertion of a bar or jacking means to aid in bringing the notch 45 in contact with the lever 47. This auxiliary means is very seldom used however, as in most cases the truck is brought to a point near the end of the rails where the vertical height from the rail to the ground is enough so that the wheel 18 may be swung down to its driving position by hand. The truck is then run off the end of the rails onto the ground. It may thus be seen that means are provided whereby my device may be operable on a mine track at a certain speed or on a mine bottom at another slower speed obtained through the geared reduction from the pinion 27 to the gear 42, and therefore has the necessary power to traverse obstructions and the rough mine bottoms which may be encountered.

Referring now to the driving mechanism, power for operating the truck may be derived from any suitable source such as a motor carried by the truck. In the embodiment illustrated I have shown an arrangement whereby the motor of a mining machine may be utilized for this purpose. This arrangement comprises a rotatable coupling link 54 which is adapted to be connected with a suitable motor driven shaft on a mining machine 3 when the mining machine is loaded in place on the truck as shown in Figure 1. Said coupling link is operatively connected with a spur gear 55 having a sleeve 56 integral therewith. Said sleeve is journaled in a support 57 mounted on the body of the rear frame 19.

The driving connections from the gear 55 to each of the sprockets 17—17 are similar in construction with the exception of the drive for the cable reel and a few minor details, so the description of one driving connection will serve for both, except in the above mentioned cases, which will be described in their order. Meshing with the gear 55 in Figure 5, is a spur gear 58 having a hub 59 integral therewith. The hub 59 is journaled in suitable bearing supports 60. Said gear 58 is keyed to a shaft 61 which extends forward to a suitable bearing in the frame 19 and extends rearward as a drive for the cable reel 22. It may also be seen that the gear 58 on the left hand side of the truck has a hub 59 integral therewith journaled in a suitable bearing support 60 and is identical with the gear 58 on the right hand side of the machine but is keyed to a shaft 62 instead of the shaft 61. It will be noted however that the shaft 62 is similar to the shaft 61 with the exception that it does not project rearwardly beyond the hub 59 to form a driving means for the cable reel 22, as does the shaft 61. It may therefore be understood, when the shaft 61 is hereafter mentioned, that said shaft is provided with the same mechanism forward of the gear 130

58 as the shaft 62 and therefore to avoid complication in this specification in describing the following driving mechanism, the shaft 61 only will hereinafter be mentioned.

5 A planetary reduction gearing with a frictional control is provided in the driving connection to the sprockets 17-17. This frictionally controlled planetary reduction gearing is of the type commonly used on mining 10 machines and trucks, and includes a drum 65 loosely mounted on the shaft 61, forward of the gear 58 and having a friction band 66 thereon. This friction band is controlled by a means which will hereinafter be described, 15 so that pressure on the drum 65 through the band 66 will cause rotation of a bevel gear 67 keyed to a hub 68 of a cage 69 which in turn carries suitable planetary pinions 70 in the well known manner of gear reduction mechanisms of this type. The bevel gear 67 drives a bevel gear 74 keyed to a shaft 75 and journaled on its hub is a suitable bearing bracket 76 on the supporting frame 19. A spur gear 77 is keyed to the shaft 75 and rotates an idler 20 gear 78. It will be noted that bevel gear 74 meshing with bevel gear 67 on the left hand side of my device is not journaled in the machine frame but has a spur gear 77 keyed to its hub. This bevel gear is keyed to a shaft 25 75^a which is supported in a suitable bearing journal (not shown) to support the bevel gear 74. The above mentioned construction is necessary to cause the sprockets 17-17 to rotate in the same direction. Rotation of the 30 idler gear 78 rotates a spur gear 79 keyed to a shaft 80. A sprocket 81 is keyed to said shaft. A driving chain 82 connects the sprocket 80 with the sprocket 17 and rotates said sprocket. Rotation of the sprockets 40 17-17 rotate the wheels 16-16 and 18-18 adaptable to drive the truck either on the rails or ground as desired.

Referring now more particularly to the details of the steering device as shown in Figures 2, 5 and 6, it may be seen that forks 85 are provided for supporting the wheels 21 and axles 20 and that said forks are pivotally mounted in the supporting frame 19 by pivot pins 87. These pins each have a crank lever 50 88 fixed to the upper portion thereof. A rack 89 is mounted transversely of the truck frame 19 and is slidable in said frame. Two cams 90, 90, are integral with the rearward portion of the rack 89 and are on each side 55 of the center of said rack. These cams are of the same construction but one cam is on the lower side of the rack 89 and the other cam is on the upper side of said rack at the opposite end thereof. A pinion 91 meshes 60 with said rack and is keyed to a vertical shaft 92, held in the supporting frame 19 and rotatable in suitable bearings in said frame. A hand wheel 93 is keyed to the upper end of said shaft. Turning of the hand 65 wheel 93 slides the rack 89 transversely of

the truck frame 19. Connecting levers 94, 94, connect the rack 89 with the crank levers 88, 88. Rotation of the hand wheel 93 therefore causes pivotal movement of the forks 85, 85, and thus turns the wheels 21, 21. Rollers 95, 95, are mounted on bell crank levers 96, 96, and ride on the cams 90, 90. One roller is mounted on the upper side of one bell crank lever while the other roller is mounted on the under side of the other bell crank lever 70 so one roller may engage the upper cam 90 on the rack 89 and the other roller may engage the lower cam 90 on the rack 89 on the opposite end thereof. The bell crank levers 96, 96, are pivoted on the opposite sides of 75 the supporting frame 19 at 97, 97. One lever arm 98 bears against lugs 99 on one end of the friction band 66. The other end of said friction band is fixed to the supporting frame 19 by an arm 100 having an adjusting screw 80 101 extending therethrough and bearing against a lug 102. Therefore, when the lever arm 98 bears on the lug 99 and forces the ends of the friction band 66 together, the friction drum 65 is held from rotation and 85 power is applied to the driving wheels. When the roller 95 is on the depressed portion of the cam 90, the ends of the friction band 66 are allowed to separate. This allows the friction drum 65 to rotate and cause 90 power to be released from the driving wheel driven by that friction drum. When operating on the rails or on the ground in a straight line the rollers 95, 95, will be on the raised portion of the cams 90 and both wheels 95 will be driven at a constant speed. When operating on the ground and it is desired to 100 turn the truck, it is only necessary to turn the hand wheel 93 according to the direction in which it is desired to turn the truck. This will cause the rack 89 to move transverse to the frame 19 which causes the wheels 21 to be turned on their vertical axes. At the same time one roller 95 will ride on the cam 90 while the other roller 95 will ride on the depressed portion of said cam which will cause power to be applied to one traction wheel and released from the other traction wheel. This quickly turns the truck about one of the 105 forward wheels (depending upon which way the truck is to be turned) as a pivot point, with the additional aid of the rearward wheels. This construction enables my mining machine truck to negotiate the mine bottom and turn sharp curves and more easily 110 pass through narrow breakthroughs or passageways.

The cable reel 22 is supported on the truck 1 to the rear of the power frame 19 by suitable brackets 103 and 104 and has connection 115 with the driving mechanism for propelling said truck by the shaft 61 which has a helical gear 105 loosely mounted near the outer end. A suitable clutch which in this case is a jaw clutch 106 operatively connects the gear 105 120

with the shaft 61. The gear 105 has driving connection with another helical gear 107 keyed to a sleeve 108 loosely mounted on a horizontal shaft 109 extending transversely to the frame 19. A means is provided whereby power to the cable reel 22 may be automatically released to prevent damage to the cable in case said cable should accidentally get caught or fouled while being wound in. A friction means is provided to automatically release power from said cable in this case, and comprises a friction disc 110 having operative connection with the sleeve 108 through jaws 111 and teeth 112. Another friction disc 113 abuts the disc 110 and has operative connection with a reel 114. Pressure of the disc 110 against the disc 113 causes rotation of the disc 113 by the disc 110 and thus drives the reel 114. The amount of pressure applied by the disc 110 determines the point at which the disc 113 will slip and thus determines the point at which power will cease to be transmitted to the reel 114. A spring 115 fits on the shaft 109 and bears against a collar 116 on the sleeve 108 at one end and a collar 117 at the other end. The tension of said spring is adjusted by a nut 118 and the tension of said spring therefore determines the amount of power applied to the reel 114 and the point at which the reel will unwind in case the cable gets caught while winding in.

In the embodiment of my invention as has been described it has been seen that a mining machine truck is provided with forward tractor driving wheels in addition to the usual flanged wheels so that my truck may be operated over a track in the usual manner, but when it is desired to transport the mining machine beyond the track, the tractor wheels may be lowered to support the forward portion of the truck and drive the truck and machine over the ground or mine bottom. It has been seen that a novel means has been provided for steering my device on the mine bottom whereby my device will quickly and sharply turn with the aid of all four wheels and that a cable is carried to supply power to my device when traversing beyond the source of power. The rearward portion of my device is supported on the usual flanged track wheels which in this case are large enough to support the weight of the rearward portion of the machine and truck on the ground.

It is advantageous to have a truck such as has here been described in my invention since there are many instances where it is not deemed advisable or economical to extend temporary tracks into the mine rooms near the working face where the mining machine is to cut. This makes it necessary to unload the machine at the room neck and drag it to the face of the coal by its draft ropes. 65 This is a hard process and takes valuable

time which is not necessary when such a truck as has been described as my invention is used. My device is especially adaptable to conditions where the coal is loaded to cars on the entry by conveyors or scraper loaders 70 since no tracks are laid to the face of the coal under such conditions and the room neck is often blocked up by the loading apparatus so that it is necessary to transport the machine to the working face through adjoining 75 rooms and breakthroughs.

While I have shown and described one form in which my invention may be embodied, it will be understood that the construction and arrangement of the various parts 80 may be altered without departing from the spirit and scope thereof. Moreover, I do not wish to be construed as limiting myself to the identical or particular construction illustrated, excepting as it may be specifically 85 limited in the appended claims.

I claim as my invention:

1. In combination with a mining machine, a truck, supporting wheels and axles therefor, driving means for a pair of track wheels 90 of said truck, auxiliary traction driving wheels eccentrically mounted on said pair of track wheel axles, and means whereby said truck may be supported and propelled on either said track wheels or said traction 95 wheels.

2. In combination with a mining machine, a truck, supporting track wheels and axles therefor, driving means for a pair of track wheels of said truck, auxiliary traction driving wheels eccentrically mounted on said track wheel axles, a single driving means for 100 said traction driving wheels and said track wheels, and means whereby said truck may be supported and propelled on either said 105 track wheels or said traction wheels.

3. In combination with a mining machine, a truck, supporting track wheels and axles therefor, driving sprockets connectable with a pair of track wheels of said truck, means 110 to drive said sprockets, auxiliary traction driving wheels eccentrically mounted on said track wheel axles, and a geared reduction whereby said traction driving wheels may be driven from said sprocket at a slower 115 speed than said track wheels.

4. In combination with a mining machine, a truck, supporting track wheels and axles therefor, driving sprockets connectable with a pair of track wheels of said truck, means 120 to drive said sprockets, auxiliary traction driving wheels eccentrically mounted on said track wheel axles on the outside thereof, and a geared reduction whereby said traction driving wheels may be driven at a slower 125 speed than said track wheels from said sprocket comprising a pinion coaxial and connectable with said sprocket, and an internal gear driven by said pinion and integral with said traction wheels. 130

5. In combination with a mining machine, a truck, supporting track wheels and axles therefor, driving sprockets connectable with the track wheels of said truck, means to drive said sprockets, auxiliary traction driving wheels eccentrically mounted on said axles adjacent said track wheels, and comprising a cylinder rotatable on a plurality of circular discs mounted eccentric of said axles 70
- 10 coaxial with said track wheels and having a traction tread on the outer periphery thereof, and an internal gear on said cylinder intermediate said discs, said internal gear meshing with and being driven by a pinion coaxial with said track wheels and connectable with said sprockets. 75
- 15 6. In combination with a mining machine, a truck, supporting track wheels, and axles therefor, driving sprockets connectable with the track wheels of said truck, means to drive said sprockets, auxiliary traction driving wheels eccentrically mounted on said forward axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement with the ground. 80
- 20 7. In combination with a mining machine, a truck, supporting track wheels and axles therefor, driving sprockets connectable with the track wheels of said truck, means to drive said sprockets, auxiliary traction driving wheels eccentrically mounted on said axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement or disengagement with the ground. 85
- 25 8. In combination with a mining machine, a truck, supporting track wheels and axles therefor, driving sprockets connectable with the track wheels of said truck, means to drive said sprockets, auxiliary traction driving wheels eccentrically mounted on said axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement or disengagement with the ground. 90
- 30 9. In combination with a mining machine, a truck, supporting track wheels and axles therefor, driving sprockets connectable with the track wheels of said truck, means to drive said sprockets, auxiliary traction driving wheels eccentrically mounted on said axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement or disengagement with the ground. 95
- 35 10. In combination with a mining machine, a truck, supporting track wheels and axles therefor, driving means for a pair of track wheels of said truck, a vertical pivot mounting for another pair of track wheels and axles, traction driving wheels eccentrically mounted with the first mentioned pair of wheel axles, and means for driving said traction wheels at a speed slower than said track wheels. 100
- 40 11. In combination with a mining machine, a truck, supporting track wheels and axles therefor, driving means for forward track wheels of said truck, a vertical pivotal mounting for rearward track wheels and axles for said truck, means to control the pivotal movement of said rearward track wheels, traction driving wheels eccentrically mounted with said forward track wheel axles, and a variable friction controlled speed means for driving said forward traction wheels. 105
- 45 12. In combination with a mining machine, a truck, supporting track wheels and axles therefor, driving means for a pair of track wheels of said truck, a vertical pivotal mounting for another pair of track wheels and axles of said truck, and means to turn said track wheels on their pivot, auxiliary traction driving wheels eccentrically mounted with said first named track wheels, means to drive said traction wheels and friction controlled means 110
- 50 to lessen the speed of one traction wheel while the speed of said other traction wheel is constant. 115
- 55 13. In combination with a mining machine, a truck, supporting track wheels and axles therefor, driving sprockets connectable with the track wheels of said truck, means to drive said sprockets, auxiliary traction driving wheels eccentrically mounted on said forward axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement with the ground. 120
- 60 14. In combination with a mining machine, a truck, supporting track wheels and axles therefor, driving sprockets connectable with the track wheels of said truck, means to drive said sprockets, auxiliary traction driving wheels eccentrically mounted on said forward axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement with the ground. 125
- 65 15. In combination with a mining machine, a truck, supporting track wheels and axles therefor, driving sprockets connectable with the track wheels of said truck, means to drive said sprockets, auxiliary traction driving wheels eccentrically mounted on said forward axles adjacent said track wheels and comprising a cylinder rotatable on a plurality of circular discs mounted eccentric of said forward axles coaxial with said track wheels and having a traction tread on the outer periphery thereof, an internal gear on said cylinder intermediate said discs, said internal gear meshing with and being driven by a pinion coaxial with said track wheels and connectable with said sprockets, and locking means to prevent rotation of said eccentrically mounted discs, and hold said traction members in engagement with the ground. 130

- therefor, driving means for a pair of track wheels of said truck, a vertical pivotal mounting for another pair of track wheels and axles of said truck, means to turn said track wheels on their pivot, auxiliary traction driving wheels eccentrically mounted with said track wheels, means to drive said traction wheels and friction controlled means to lessen the speed of one traction wheel while the speed of said other traction wheel is constant, simultaneously as said track wheels are pivoted on their vertical axes.
14. In combination with a mining machine, a truck, supporting track wheels and axles therefor, driving means for a pair of track wheels of said truck, a vertical pivotal mounting for another pair of track wheels and axles of said truck, means to turn said track wheels on their pivot, auxiliary traction driving wheels eccentrically mounted with said driven track wheels, means to drive said traction wheels and friction controlled means to lessen the speed of one traction wheel while the speed of said other traction wheel is constant, simultaneously as said other track wheels are pivoted on their vertical axes, and means whereby said truck may be propelled on either said track wheels or said traction wheels, rendering the wheels not propelling said truck inoperative.
15. In combination with a mining machine, a truck, supporting track wheels and axles therefor, driving means for a pair of track wheels of said truck, a vertical pivotal mounting for another pair of track wheels and axles of said truck, means to turn said track wheels on their pivot, auxiliary traction driving wheels eccentrically mounted with said track wheels, and a friction controlled planetary geared reduction means to drive said traction wheels and to lessen the speed of one traction wheel while the speed of said other traction wheel is constant at the same time said other wheels and axles are pivoted on their vertical axes.
16. In combination with a mining machine, a truck operable on mine rails or a mine bottom, supporting track wheels and axles therefor comprising a pair of supporting track wheels and a pair of supporting driving wheels, auxiliary supporting traction driving wheels therefor, means to render said traction driving wheels operative and said track driving wheels inoperative and vice-versa, a steering means for said truck comprising a vertical pivotal mounting for said supporting track wheels, means to pivot said track wheels, and drive means for said auxiliary traction driving wheels whereby the power to one traction wheel may be lessened while the power to said other traction wheel remains constant, connected to and operable by said pivoting means for said rearward track wheels.
17. In combination with a mining machine,

a truck operable on mine tracks or a mine bottom, supporting wheels and axles therefor comprising a pair of vertically pivotally mounted guiding track wheels, a pair of driving track wheels forward of said guiding track wheels, an auxiliary pair of traction driving wheels supported on said track driving wheel axles, a common drive sprocket on each side of said truck to simultaneously drive said tractor and said track driving wheels, means to drive said drive sprockets from said mining machine comprising a system of reduction gearing connectable with said mining machine and said sprockets and having a frictionally controlled planetary reduction gearing therein for each of said sprockets, a means whereby either said track driving wheels or said tractor driving wheels may be rendered inoperative and non-supporting while one pair of said driving wheels is operative, a steering means for said truck operable while traversing a mine bottom comprising a means to turn said pivotally mounted rearward track wheels and simultaneously relieve power from said forward traction wheel on which said truck is to turn as an axis, comprising a means operable with said turning device to relieve pressure on one planetary frictionally controlled gearing system and apply the pressure on said opposite planetary frictionally controlled gearing system, and a frictionally controlled cable reel to the rear of said truck and driven by said driving mechanism for said truck.

18. In combination with a mining machine, a truck operable on mine rails or a mine bottom, supporting track wheels and axles therefor comprising rearward supporting track wheels and forward supporting driving track wheels, means to drive said track wheels, auxiliary supporting forward traction driving wheels therefor, means to render said traction driving wheels operative and said track driving wheels inoperative and vice-versa, a steering means for said truck, operable while said truck is traversing a mine bottom comprising vertically pivotally mounted track wheels, means to control the pivotal movement of said track wheels, and a friction controlled means to drive said auxiliary forward traction driving wheels whereby the power to one traction wheel may be lessened while the power to said other traction driving wheel remains constant, operable by said pivoting control means for said rearward track wheels.

19. In combination with a mining machine, a truck operable on mine rails or a mine bottom, supporting track wheels and axles therefor comprising rearward supporting track wheels and forward supporting driving track wheels, means to drive said track wheels, auxiliary supporting forward traction driving wheels therefor, means to render said traction driving wheels operative and said track

- driving wheels inoperative and vice-versa, a steering means for said truck, operable while said truck is traversing a mine bottom comprising a vertically pivotally mounted track wheels, means to control the pivotal movement of said track wheels, and a friction controlled planetary geared driving means for said auxiliary forward traction driving wheels whereby the power to one traction wheel may be lessened while the power to said other traction driving wheel remains constant, operable and controlled by said turning means for said rearward track wheels. 20. In combination with a mining machine, a truck operable on mine rails or a mine bottom, supporting track wheels and axles therefor comprising rearward supporting track wheels and forward supporting driving track wheels, means to drive said track wheels, auxiliary supporting forward traction driving wheels therefor, means to render said traction driving wheels inoperative and said track driving wheels inoperative and vice-versa, a steering means for said truck, operable while said truck is traversing a mine bottom comprising vertically pivotally mounted track wheels, means to control the pivotal movement of said track wheels, and a friction controlled planetary geared driving means for said auxiliary forward traction driving wheels whereby the power to one traction wheel may be lessened while the power to said other traction driving wheel remains constant, simultaneously as said rearward wheels are turned on their vertical pivotal axes. 21. In combination with a mining machine, a truck operable on mine rails or a mine bottom, supporting track wheels and axles therefor comprising rearward supporting track wheels and forward supporting driving track wheels, means to drive said track wheels, auxiliary supporting forward traction driving wheels therefor, means to render said traction driving wheels inoperative and said track driving wheels inoperative and vice-versa, a steering means for said truck, operable while said truck is traversing a mine bottom comprising vertically pivotally mounted track wheels, means to control the pivotal movement of said track wheels, and a friction controlled planetary geared driving means for said auxiliary forward traction driving wheels whereby the power to one traction wheel may be lessened while the power to said other traction driving wheel remains constant, simultaneously as said rearward wheels are turned on their vertical pivotal points and controlled and operated by said turning means for said rearward track wheels. 22. In combination with a mining machine, a truck, supporting wheels and axles therefor comprising a pair of guiding track wheels, a pair of driving track wheels and an auxiliary pair of traction driving wheels supported on said track driving wheel axles, and a common driving means for said traction and said track driving wheels comprising a motor connectable therewith by means of gearing including a frictionally controlled planetary gear device. 23. In combination with a mining machine, a truck, supporting wheels and axles therefor comprising a pair of guiding track wheels, a pair of driving track wheels and an auxiliary pair of traction driving wheels supported on said track driving wheel axles, and a common drive sprocket on each side of said truck to simultaneously drive said traction and said track driving wheels, a means to drive said sprocket comprising a motor connectable therewith through drive chains and a gearing including a frictionally controlled planetary gear device for each of said drive sprockets. 24. In combination with a mining machine, a truck, supporting wheels and axles therefor comprising a pair of guiding track wheels, a pair of driving track wheels and an auxiliary pair of traction driving wheels supported on said track driving wheel axles, and a common drive sprocket on each side of said truck to simultaneously drive said traction and said track driving wheels, a means to drive said sprocket comprising a motor connectable therewith through drive chains and a gearing including a frictionally controlled planetary gear device for each of said drive sprockets, and means to control said frictionally controlled planetary geared reduction whereby an equal maximum amount of power may be given to both of said traction driving wheels, or a maximum amount of power may be transmitted to one traction wheel while a minimum amount of power is transmitted to said other traction wheel.
